UNITED STATES PATENT OFFICE.

FREDERICK J. KALDENBERG, OF NEW YORK, N. Y.

DESIGN FOR AN UMBRELLA-HANDLE.

SPECIFICATION forming part of Design No. 11,732, dated April 13, 1880.

Application filed February 26, 1880. Term of patent 3 $\frac{1}{2}$ years.

To all whom it may concern:

Be it known that I, FREDERICK J. KALDENBERG, a citizen of the United States, residing at New York, in the county and State of New York, have invented and produced a new and original Design for Umbrella or Parasol Handles, of which the following is a specification, reference being had to the accompanying drawing, forming part thereof.

My invention has for its object the production of a novel and fanciful design for the handles of umbrellas or parasols; and its leading feature consists in a figure upon the handle representing a lyre enriched by appropriate ornamentation.

In the accompanying drawing, which fully illustrates my newly-invented design, *a* is the body of the handle, which is preferably round and unadorned. *b* is a stringed musical instrument, intended to represent in general outline the ancient lyre. Beneath the lyre, and encircling the handle near the top, is an ornament, *c*, of carved work, in the form of leaves intermixed and pendent, representing a garlanded staff.

To increase the elegance of the design the strings *dd* of the lyre may be of silvered or gilded

wire. Any appropriate or symbolical ornamentation—such as delicate tracery or representation of vines and flowers—may be carved 30 on the surface of the lyre, entirely or partly covering the same, to render more elegant and attractive to the eye.

What I claim as new, and desire to secure by Letters Patent, is—

1. The design for an umbrella or parasol handle, consisting of the representation of a lyre placed on the top or head of the handle, as described, and shown in the accompanying drawing. 35

2. The design for an umbrella or parasol handle, consisting of the representation of the ancient lyre with depending leaf-like ornaments, substantially as described, and shown in the accompanying drawing. 40

3. The design for an umbrella or parasol handle, consisting of the representation of a lyre and garlanded staff, substantially as herein shown and described. 45

FRED. J. KALDENBERG.
